UNITED STATES PATENT OFFICE.

HENRY D. RUSSELL, OF NAUGATUCK, CONNECTICUT.

LOCK.

Specification of Letters Patent No. 15,708, dated September 9, 1856.

To all whom it may concern:

Be it known that I, H. D. RUSSELL, of Naugatuck, in the county of New Haven and State of Connecticut, have invented certain new and useful Improvements in the Mode of Constructing Locks for Doors and other Purposes, of which the following description, illustrated by the accompanying drawings and references, is sufficiently clear 10 and comprehensive to enable persons of competent ability to make and use my invention.

The nature of my improvement relates to a certain combination of parts, by which I more conveniently accomplish the object of 15 locking and unlocking the door than has heretofore been done, and also in providing a new device for moving the bolt or bolts of the lock, by which I can release the knob by the key allowing it to be turned at 20 pleasure without affecting the bolt.

Figure 1 is a side elevation of the lock with the front plate removed and the parts represented in their natural unlocked position. Fig. 2 is the same view with the main 25 bolt made fast, or locked.

A, A, are the side plates of the lock.

B is the main bolt which is slotted to receive the spring Y and the inclosed smaller bolt C, and forked at b, b, to receive the 30 stem D as a guide. D has a bearing in both plates and receives the stem of the knob, which is not represented. It is made fast to the crescent disk E pointed at e, e, as represented by dotted lines. The small bolt 35 C has a pin S projecting vertically from its sides both back and front. Upon the door

knob being turned either point of the crescent E catches the pin upon the back of the bolt C and forms with the inner surface or edge of such crescent an inclined plane upon 40 which the pin slides to draw the bolt C, and its attachment the main bolt B made fast to it by being locked by the cross bar F. The form of the cross bar F is fully represented in both its positions by the 45 drawings Figs. 1 and 2. It is moved by the key which passes through the openings in the plate A, at G. When the key is turned the cross bolt F locks between the stationary pins I and J and prevents the 50 main bolt from being operated by the smaller bolt C. The knob is allowed to revolve at all times when the door is locked in consequence of the front pin S rising upon the inclined plane at i and thus preventing the point of crescent from catching 55 S upon the opposite side of C.

We have in this arrangement but one spring and but one bolt used for the purpose of catching or locking the door. 60

I claim—

Liberating the knob and its stem from all connection with the main bolt in freeing the crescent plate E, by the movement of the smaller bolt C, as specified produced by the 65 cross bar F or its equivalent operated by the key of the door, the whole constructed and arranged substantially as set forth.

HENRY D. RUSSELL.
